UNITED STATES PATENT OFFICE

127,493

DESIGN FOR A COMBINATION CIGAR CABINET AND CIGARETTE DISPENSING MACHINE

David Safier, University Heights, Ohio

Application January 23, 1941, Serial No. 98,349

Term of patent 7 years

To all whom it may concern:

Be it known that I, David Safier, a citizen of the United States, residing in the city of University Heights, county of Cuyahoga, and State of Ohio, have invented a new, original, and ornamental Design for a Combination Cigar Cabinet and Cigarette Dispensing Machine, of which the following is a specification, reference being had to the accompanying drawing, forming a part thereof.

Figure 1 is a front elevation of the combined

cigar cabinet and cigarette dispensing machine with the cigar cabinet cover in open position, showing my new design; and

Figure 2 is a side elevation of the same with the cigar cabinet cover partly closed.

I claim:

The ornamental design for a combination cigar cabinet and cigarette dispensing machine, substantially as shown.

DAVID SAFIER.
